[57] CLAIM

The ornamental design for a IC preheating block, as shown
and described.

DESCRIPTION

FIG. 1 is a perspective view, taken from the top, left front,
corner, as viewed in FIGS. 1 and 2, of an IC preheating
block, showing my new design;

FIG. 2 top plan view thereof;

FIG. 3 is a bottom plan view thereof;

FIG. 4 is a top end view thereof, the bottom end side view
being a mirror image of the top end side view; and,FIG. 5 is a right side view thereof, the left side view being
a mirror image of the right side view.
